US0D1106050S

(12) **United States Design Patent** (10) **Patent No.:** **US D1,106,050 S**
(45) **Date of Patent:** **** Dec. 16, 2025**

(54) **SOLAR PANEL**

(71) Applicant: **Feng Liu**, Guangdong (CN)

(72) Inventor: **Feng Liu**, Guangdong (CN)

(**) Term: **15 Years**

(21) Appl. No.: **29/995,866**

(22) Filed: **Mar. 28, 2025**

(51) **LOC (15) Cl.** 13-04

(52) **U.S. Cl.**

USPC **D13/102**

(58) **Field of Classification Search**

(57) **CLAIM**

The ornamental design for a solar panel, as shown and described.

DESCRIPTION

FIG. 1 is a first perspective view of a solar panel showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1; and,

FIG. 9 is an enlarged view of the solar panel labeled portion 9 in FIG. 1.

The broken lines in the drawings depict portion of the solar panel that form no part of the claimed design. The dash dot broken lines encircling portions of the solar panel illustrate enlargements that form no part of the claimed design.

1 Claim, 9 Drawing Sheets
